VARIABLE RESISTANCE

Benjamin B. Scott, Schenectady, N. Y., assignor
to General Electric Company, a corporation of
New York

Application August 27, 1949, Serial No. 112,722

11 Claims. (CL 201—62)

1

My invention relates to variable resistances, and more particularly to precision variable resistances of the type in which the resistance wire is wound in turns on a suitable support and an electric contact is moved over bared portions of the turns to vary the portion of the resistance included in an electrical circuit, and has for its object means for reducing the resistance value of the steps in the change of the resistance as the contact moves over the turns and for averaging variations in the resistance of the wire.

In the simplest form of variable resistance, which is a straight wire with a movable contact or brush, any desired change in resistance variation can be obtained as a function of the brush movement. However, when this same wire is wound on a suitable support in a plurality of turns with a brush sliding over the turns, the resistance obviously changes in steps with brush movement, the value of each step being the resistance of a turn upon movement of the brush from one turn to the other. A reduction in value of resistance steps may be obtained by suitably increasing the length of the turn wound resistance so as to decrease the resistance of each turn but that is unsatisfactory when compactness is required. Accordingly, a further object of the invention is a reduction in the step by step resistance change with brush movement while retaining the advantage of a short, compact resistance unit.

Another disadvantage of turn wound resistances is that the unit length resistance of the wire itself varies because of manufacturing variations in the diameter of the wire and, accordingly, another object of my invention is to average substantially such variations in the resistance of the wire.

In carrying out my invention in one form, I provide at least two spaced apart brushes for a turn wound resistance, which brushes are connected in parallel with a resistance in series with at least one brush and spaced apart a distance sufficient to include between them a plurality of the turns of the resistance sufficient to average the inherent wire resistance variations. For minimum step by step resistance change, it is desirable that the currents in the brushes be substantially equal and, accordingly, in one form of my invention, when two brushes are used, I connect in series with one brush, preferably the lagging brush, a resistance which is substantially the same as the value of the resistance wire between the two brushes, whereby the resistance change is reduced to one half its value with a single brush.

For a more complete understanding of my invention, reference should be had to the accompanying drawing, Fig. 1 of which is a diagrammatic representation of a wound resistance unit

5 with two brushes embodying my invention; Fig. 2 is an enlarged fragmentary view showing the relative arrangement of the brushes; Fig. 3 shows a modified form of my invention utilizing three brushes in spaced relation with each other; while Figs. 4 and 5 are modified forms showing the application of my invention to potentiometer resistances utilizing, respectively, two and three brushes.

Referring to the drawing, in Fig. 1 the resistance wire 10 is wound in turns on an electrical insulating support or card 11 shown as a strip of suitable rigid electrically insulating material, such as a plastic or fiber material. Although the wire turns extend around the support, it will be understood that other turn shapes may be used such as passes back and forth on one side of the support. For variation of the amount of the resistance included in an electric circuit of which 10 the conductors 12 and 13 form a part, two electric contacts, shown as brushes 14 and 15, are provided which engage bared portions of the turns on the upper edge, as shown, of the resistance unit. The brushes 14 and 15 are suitably mounted on an electrically insulating support 16 which is movable in predetermined spaced parallel relation with the upper edge of the resistance unit so that the brushes, shown as made of a suitable spring material, slide over the resistance turns.

20 The brushes 14 and 15 are spaced apart a predetermined distance so as to include between them a predetermined number of resistance turns of sufficient number to average out the variations in the output characteristic of the resistance unit.

25 In other words, these turns may comprise wire portions having a smaller diameter and hence greater resistance than normal and other portions having a diameter greater, and hence lower resistance, than normal, thus producing plus and minus deviations from a desired linear output characteristic.

30 Their inclusion in series between the two brushes in parallel with the resistance 20 has the effect of averaging the resistance variations at the brush contact points so that the resistance output at connection 12 materially improves linearity of the output characteristic of the unit. In a resistance wound of .0015 inch diameter wire, for example, the number of turns included between the brushes may be 500.

35 In precision wound resistors each turn is exactly spaced from the preceding turn to give the desired resistance characteristics with respect to the brush movement with consequent unequal spacing of the turns as turn resistances vary. 40 Because of this unequal spacing of the turns, the brushes ordinarily do not each short circuit a turn at the same time and, consequently, the resistance of the wire between the brushes remains substantially constant. This condition is 45 shown in Fig. 2 of the drawing, in which the

brush 15 is about to move into the space between the turn portions 17 and 18 upon further movement toward the right hand, as seen in the drawing, thereby to short circuit the turn between the portions 17 and 18 while, at the same time, the brush 14 obviously maintains its engagement with the turn or portion 19. It will be obvious from the above description in connection with Fig. 2 that the ideal spacing between brushes 14 and 15 would be a spacing distance equal to an integral multiple of the anticipated average resistor turn spacing plus one-half of the anticipated turn spacing in order that the brushes 14 and 15 be completely "out of phase" in their travel across the resistor wire turns. Likewise, with the embodiments of Figs. 3 and 5, involving the use of three brushes, the ideal spacing would include a one-third turn spacing and for a larger number of brushes the fractional turn spacing brush spacing increment would in each case be similarly dependent on the number of brushes employed.

To effect the maximum reduction in resistance steps, the division of current between the brushes 14 and 15 should be substantially equal. For this purpose, a current-limiting resistance 20 is inserted in series with the brush 14 of Fig. 1, the other end of this resistance and the brush 15 being connected electrically to the conductor 12. In the two-brush arrangement of Fig. 1, this resistance should be equal to the resistance between the brushes 14 and 15. It will be noted that the wire resistance between the brushes 14 and 15 is connected in parallel with the resistance 20. With this arrangement, the resistance steps are reduced to the equivalent of one-half turn, because each turn is carrying one-half current in the parallel circuit. When each turn is added to the circuit between conductor 13 and brush 14, its current doubles, with consequent one-half turn resistance increase effect.

In the arrangement of Fig. 3, we have shown the use of three brushes, 21, 22 and 23, secured on a movable insulating support 24 so that the two outside brushes engage the resistance unit 25 in equally spaced relation with the central brush. In this case the values of resistors 26 and 27 are again chosen for equal brush current division. With this arrangement, the current increases one-third in each turn as it is included in the circuit and each resistance step is reduced to one-third as compared to a single brush.

In Figs. 4 and 5, I have shown suitable arrangements for use with potentiometer resistance units where the direction of current flow through the resistance unit to the brushes may not always be the same or where brush current is of negligible magnitude. In Fig. 4, the resistances 28 and 29 may be equal, respectively, to substantially one-half the resistance between the brushes 30 and 31, attaining a reduction in resistance steps in a manner similar to that described above. The resistances 28 and 29 have a voltage take-off point at their common connection, wire 32.

In the three-brush arrangement shown in Fig. 5, the resistances 33, 34, and 35 may be each substantially equal to one-half the resistance between the two outside brushes 36 and 37, the two outside brushes being equally spaced from the central brush. It will be understood that in the embodiments of Figs. 4 and 5 the brush resistances 28, 29, and 33, 34, and 35 may advantageously be of higher resistance values than those stated, although the resistance values stated have been found to give satisfactory results and they

should be taken as recommended minimum resistance values.

While I have shown a particular embodiment of my invention, it will be understood, of course, that I do not wish to be limited thereto since many modifications may be made and I therefore contemplate, by the appended claims, to cover any such modifications as fall within the true spirit and scope of my invention.

What I claim as new and desire to secure by Letters Patent of the United States is:

1. A variable resistor comprising a resistance wire wound in a plurality of turns on a support, a pair of electric contacts, means for supporting said contacts in spaced relation with each other in contact with said resistance wire, said support being movable along said resistance wire thereby to move said contacts over said turns, electric connections for connecting said contacts together, a resistance included in said connections with at least one of said contacts, said electrically interconnected contacts together comprising one outgoing resistor connection.

2. A variable resistor comprising a resistance wire wound in a plurality of turns on a support, a plurality of electric contacts, means for supporting said contacts in spaced relation with each other in contact with said resistance wire, said support being movable along said resistance wire thereby to move said contacts over said turns, electric connections for connecting said contacts together, and resistances included in said connections with said contacts having values such as to maintain substantially equal currents in said contacts, said electrically interconnected contacts together comprising one outgoing resistor connection.

3. A variable resistor comprising a resistance wire wound in a plurality of turns on a support, a fixed outgoing connection at one end of said wire, a pair of electric contacts, means for supporting said contacts in spaced relation with each other in contact with said resistance wire, said support being movable along said resistance wire thereby to move said contacts over said turns, electric connections for connecting said contacts together to form a movable outgoing connection, a resistance included in said connection with the one of said contacts nearest said fixed outgoing connection having a resistance value substantially the same as the value of the resistance of said wire between said contacts so as to maintain substantially equal currents in said contacts.

4. A variable resistor comprising a resistance wire wound in a plurality of spaced turns on a support, a pair of contacts, means for supporting said contacts in spaced relation with each other in contact with said resistance wire, said support being movable along said resistance wire thereby to move said contacts over said turns, said contacts being mounted on said support in such spaced relative positions as to average variations in the resistance of said wire between said contacts, electric connections for connecting said contacts together, and a resistance included in said connections with at least one of said contacts.

5. A variable resistor comprising a resistance wire wound in a plurality of spaced turns on a support, a plurality of electric contacts, means for supporting said contacts in spaced relation with each other in contact with said resistance wire, said support being movable along said resistance wire thereby to move said contacts over said turns, said contacts being mounted on said

support in such spaced relative positions as to average variations in the resistance of said wire between said contacts, electric connections for connecting said contacts together to form a movable outgoing resistor connection, and resistances included in said connections with said contacts having values such as to maintain substantially equal currents in said contacts.

6. A variable resistor comprising a resistance wire wound in a plurality of spaced turns on a support, a fixed outgoing connection at one end of said wire, a pair of electric contacts, means for supporting said contacts in spaced relation with each other in contact with said resistance wire, said support being movable along said resistance wire thereby to move said contacts over said turns, said contacts being mounted on said support in such spaced relative positions as to average variations in the resistance of said wire between said contacts, electric connections for connecting said contacts together, and a resistance included in said connections with the one of said contacts nearest said fixed outgoing connection having a value substantially the same as the value of the resistance of said wire between said contacts so as to maintain substantially equal currents in said contacts thereby to reduce the effective resistance step to substantially one-half turn.

7. A variable resistor comprising at least one fixed outgoing terminal and one movable outgoing terminal, said movable outgoing terminal being connected to a plurality of electrically and mechanically interconnected resistor contact brushes, said electrical interconnections including current-limiting resistors.

8. A resistance wire wound electrical resistor having a movable contact device comprising a plurality of mechanically and electrically interconnected contact brushes for contacting axially closely spaced points on said resistor, said electrical interconnections including electrical resistance, and an outgoing terminal connected to said movable contact device.

9. A movable contact terminal device for a resistance wire wound electrical resistor, said device comprising at least two contact brushes, said brushes being both mechanically and electrically interconnected, said electrical intercon-

nnection including electrical resistance, said brushes being axially spaced by a distance equal to an integral multiple of the anticipated average resistor turn spacing plus a fractional portion thereof, the fraction having a denominator equal to the number of brushes.

10. A movable contact structure for establishing an outgoing connection for a resistance wire-wound electrical resistor comprising a plurality of contact brushes for contacting the windings of said resistor, resistors connected in series with a number of said brushes at least as great as one less than the total number of said brushes, said brushes being mechanically connected and spaced from one another by distances equivalent to whole multiples of the anticipated average resistor turn spacing plus fractional multiples of said spacings, said fractional multiples comprising a fraction whose denominator is equal to the number of said brushes.

11. A resistance wire wound electrical resistor having a fixed outgoing connection at one end thereof, a movable outgoing connection contact structure comprising a plurality of contact brushes for contacting the windings of said resistor, resistors connected in series with a number of said brushes at least as great as one less than the total number of said brushes, said series connected resistors having respective resistance values dependent upon the proximity of the connected brushes to said fixed outgoing connection, the higher value resistors being connected to the closer brushes.
